UNITED STATES PATENT OFFICE.

OTTO H. DE LAPOTTERIE, OF NEW BRIGHTON, PENNSYLVANIA, ASSIGNOR TO ROY H. SMITH, OF KENT, OHIO.

APPARATUS FOR MAKING RIVETS.

Application filed December 7, 1918, Serial No. 265,752. Renewed May 17, 1923.

To all whom it may concern:

Be it known that I, OTTO H. DE LAPOTTERIE, a citizen of the United States, residing at New Brighton, in the county of Beaver and State of Pennsylvania, have invented certain new and useful Improvements in Apparatus for Making Rivets, of which the following is a specification.

This invention relates to an apparatus for continuously making rivets and bolts from blanks whose heads only are heated to the forging temperature during the operation of making the rivet or bolt.

Heretofore articles made from blanks in the manner described have been made by the stop motion method. The stop motion method of making rivets and bolts briefly described comprises,—first, a plain open die rivet and bolt machine; second, an ordinary heating furnace; and, third, the following method of operation.

Stock which is usually round rod or bar steel suitable for making rivets or bolts is cut cold into blanks of desired length in a power shear. From the power shear the blanks are taken to the heating furnace where the man who looks after the heating of the blanks places them side by side in the furnace in such a manner as to heat one end of the blanks.

As soon as the end portion of the first blank placed in the furnace is heated to a forging temperature, the furnace man quickly removes it from the furnace with a pair of hand tongs and passes it to the rivet and bolt machine operator who in turn takes it in a pair of hand tongs and places it between two adjacent faces of suitably grooved gripping dies in the machine, in

such a manner that the end of the blank protruding through the dies will touch a stop gauge which regulates the amount of stock to go into the head of the article. The machine operator while still holding the blank in the tongs places his foot on a lever which causes the machine to operate and forge the portion of the blank which protrudes beyond the end of the gripping dies into a head. When the head of the

rivet or bolt is formed the operator removes his foot from the foot treadle at a time which will stop the machine with gripping dies sufficiently apart to allow him to remove the headed article from between the two halves of the dies. When done prop-

erly, this also leaves the gripping dies sufficiently open to permit of ready entrance of the next blank, when the operations described are repeated.

From the foregoing description it will readily be seen that all operations connected with this method of manufacture must of necessity come to a stand still after each rivet or bolt is made, making the entire method subject to the serious disadvantage of becoming inoperative at least one-half of the time, which results in loss of considerable production, as will readily be appreciated.

Another disadvantage is that, with the method referred to, solid die rivets or bolts have not been made from blanks heated in the manner described. The advantage of an article such as a rivet or bolt made in a solid die as compared with such an article made in an open die, is that the solid die being a single block of steel with an orifice in it for holding the shank of an article during forging of the head, no fins are formed under the head of such an article. Such fins are formed under the head of a rivet or bolt when open dies are used, because some of the metal which forms the underside of the head, is forced in between the two adjacent die sections which of necessity compose open dies. By my invention the difficulties described are eliminated.

The invention will be readily understood from the accompanying drawings, in which—

Fig. 1 is an elevation of the apparatus used, parts being shown in section;

Fig. 2 is a plan of Fig. 1;

Fig. 3 is a vertical section;

Figs. 4 and 5 are fragmentary views, in plan and elevation respectively, of the blank carrier chain;

Fig. 6 is an elevational view on an enlarged scale of intermittent motion mechanism; and

Fig. 7 a section taken on line 7—7, Fig. 6.

Referring to the drawings, I generally designate a rotary automatic blank-feeding hopper which may advantageously consist of a drum 1 mounted on a shaft 2 carried on a suitable supporting structure 3. On the side opposite the shaft 2 the drum 1 is provided with a bell-mouth opening 4 for charging the hopper. The rivet blanks B are cut cold by any suitable blanking ma-

90

100

105

110

chine from which they are delivered by suitable transfer mechanism to the bell-mouth opening 4. The drum 1 is provided with radial slots 5 of the length of the rivet blanks and of a width slightly smaller than the orifice 75' of the stationary die 75 in the heading machine generally designated III, which is preferably of the solid die single blow type.

10 The slots 5 are made slightly smaller in diameter than the orifice in the solid die 75 to make certain that any blank gaged or passed out of the hopper will enter the die with little effort. The rotary drum or hopper 1 is proportioned to hold a sufficient number of blanks so that during the rotary movement of the drum the blanks are continuously turned over and, tumbling over one another, subject each other to shocks and 20 vibrations which operate to remove excess scale or dirt before being passed to the die in the heading machine.

In the interior of the drum 1 slot guards 6 are provided which prevent a blank entering an outlet slot 5 endwise, a blank being 25 able to enter slots 5 only when it lies substantially parallel to the axis of the drum in front of a slot.

Below the drum 1 is a hopper chute 7 30 through which the blanks may pass from the hopper to the blank carrier chain 10 to be subsequently described in detail. This hopper chute 7 is of such a height as to hold in reserve a sufficient number of blanks to assure time for blanks in the hopper entering the radial slots 5 and also allow time for cleaning and slightly rounding of cutting edges on the ends of the blanks by the tumbling action of the hopper to thereby prevent 40 injury to the orifice of the solid die 75.

Adjacent the lower end of the chute 7 is provided an automatic blank cut-off 8 for regulating the flow of blanks to the carrier chain 10. This cut-off 8 may be operated by 45 a simple lateral movement of sufficient extent to allow a blank to pass to the blank carrier chain at the proper time to fill successive pockets 11 of the chain. For the sake of simplicity no translating mechanism 50 for operating the cut-off 8 has been shown, but it is obvious that the cut-off may be operatively connected by simple means to any part of the mechanism for progressively advancing the blanks from the chute 7 to and 55 through the heading machine.

The lower half of the drum 1 is surrounded by a guard 9 for preventing the blanks from leaving the hopper at points other than through the chute 7. This guard has 60 perforations 9' to permit the dirt and scale released from the blanks to leave the hopper. This guard is shown as connected to the chute, but it is obvious that it may be supported in any other suitable manner.

65 The blank carrier chain previously re-

ferred to forms part of a device for heating the blanks, such device being generally designated by the character II. The heating device consists principally of a furnace structure having a combustion chamber, a 70 conveyer system including the blank carrier chain 10, means for intermittently advancing the chain and special arrangements whereby only one end of each blank is heated to forging temperature while the remaining part is kept relatively cool. The furnace, which may be of any suitable design, comprises preferably the usual masonry work 12 providing a centrally located combustion chamber 13 closed at the top by a 75 removable tile 13'. The cast iron furnace fronts, with the customary stay bolts and bracing, may be of the usual design.

The endless blank carrier chain 10 is carried by sprocket wheels 14 and 14' supported 80 on suitable frame work at opposite ends of the furnace structure and passes through openings 15 in the furnace fronts over a guide shelf 16 extending substantially horizontally through the furnace structure. As 85 is clearly indicated in Fig. 3, the guiding surface of the shelf 16 is inclined so that the chain 10 and the blanks carried thereby are also inclined and have a tendency to move to the lower side. The width of the 90 chain 10 is smaller than the length of the blanks B so that the blanks project beyond one side thereof. The width of the chain is so chosen that the projecting part of the blanks corresponds to the portion which it 95 is intended to heat.

The shelf 16 is so located that the projecting portions of the blanks extend into the combustion chamber 13 and are thereby exposed to the flame and gases of combustion 100 while the remaining portion is protected. The inclination of the shelf 16 has the purpose to prevent the blanks from being thrown by jars and vibrations on the chain 105 into the combustion chamber. 110

To keep the chain in a straight line and to that extent hold the projecting ends of the blanks in alignment, the shelf 16 has a limiting shoulder 16' at the lower part thereof. In order to be able to regulate the amount 115 of projection of different blanks, a guide rail 17 is provided which may be adjusted in the direction of the length of the blanks. By means of the shoulder 16' and the guide rail 17 it is made possible to control the extent to which the blanks are to be heated and 120 uniformity of heating is attained.

Above and below the shelf 16 and the chain 10 are supported on suitable frame work cooling tanks 18 and 19 respectively. 125 These tanks extend toward the combustion chamber 13 sufficiently far to effect a cooling of so much of the blanks as it is intended to keep relatively cold. Water or other cooling fluid may be circulated through 130

tanks 18 and 19 by pipes 20. Safety applications, such as valves 21, may be resorted to to relieve the cooling system from any pressure which might result from negligence or other unforeseen circumstances.

It is advisable to make the tanks in sectional units and a continuous angle iron 22, running the full length of the furnace in such a manner as to support the side of the cooling tanks nearest the combustion chamber, is provided for the purpose of eliminating the joints resulting from dividing the cooling tank into small units, which joints might interfere with the satisfactory riding of blanks through the surface passage.

Vertically below the tanks 18 and 19 and protected against the furnace heat is a tank 23 in which relatively cool water is maintained by circulation at a level which permits the lower or returning part of the blank carrier chain to sag through the water after its passage through the furnace to be thereby cooled.

The length of the combustion chamber depends upon the number of blanks it is desired to heat in a given time. If for instance 60 blanks should be desired per minute and it takes two minutes to heat a portion of a blank to the degree of heat necessary for forging it, then the length of the combustion chamber and the effective part of the blank carrier must be proportioned to accommodate 120 blanks.

As a source of heat are shown oil or gas burners 24 connected with the combustion chamber by flame passage 25. Fire-brick baffles 26 are so disposed in the combustion chamber 13 as to spread and guide the flames as they leave the oil burners 24 and to protect the cooling systems as much as possible against the heat. Blowers 27 may be used to direct blasts of air into the flames to support the combustion in the combustion chamber.

By the arrangement described, the portions of the blanks B projecting into the combustion chamber are heated to the desired degree during their passage through the chamber, while the remaining portion of the blanks are kept relatively cool.

The sprocket wheels 14 and 14' of the carrier chain 10 are connected to sprocket wheels 28 and 28' of a second chain mechanism located outside the heating device. As indicated most clearly in Fig. 2, sprocket wheel 14 is directly connected to sprocket wheel 28 by a shaft 29 mounted in bearings 30 on a suitable support. Sprocket wheel 14' is connected to sprocket wheel 28' through a shaft 31 and intermediate gearing 32, the particular disposition and structural arrangement of parts not permitting a direct connection. However, as is obvious, the connection indicated may be

varied in various ways and suiting particular requirements. The shaft 31 is mounted in a bearing 33 and the gear mechanism 32 on a bracket 32' which also serves as a support for the shaft 31.

The driving chain 34 on sprocket wheels 28 and 28' passes preferably over guide pulleys 35 to avoid jerks and jars which would be due to the intermittent motion and the alternate sagging and stretching of the chain.

In order to intermittently advance the chain mechanism and the blanks, the following mechanism has been resorted to:

A horizontal rod 36 is shiftably mounted in brackets 36' adjacent the driving chain 34. This shaft carries a laterally projecting pin 38 on which a roller 39 is mounted. An eccentric 40 connected to the power drive of the machine in any suitable manner carries an eccentric rod 41. A lever 42 supported intermediate its ends by a pivot 43 on a bracket 44 is connected at one end to the lower end of the eccentric rod 41 and carries at its free end a wedge 45 which may be adjusted by a bolt 46. A backing block of steel may be attached to the bracket 44 to reinforce the fulcrumed wedge lever 42. The eccentric rod may be lengthened or shortened by a nut 47.

By means of a spring 48 connected at one end to the rod or shaft 36 and at the other end to a stationary support 49 the shaft 36 is given a tendency to return in one direction and to force the roller 39 against the wedge 45. As the reciprocation motion of the eccentric rod 41 is transmitted through the lever 42 to the wedge 45, the wedge operates to reciprocate the roller 39 and with it the rod 36.

To the rod 36 are pivotally connected pawls 50 and 50' for engagement with ratchet wheels 51 and 51' respectively, the former being attached to shaft 2 of the hopper 1 and the latter to shaft 29 of the sprocket wheel 28.

The heated blanks are successively delivered from the furnace to a chute 52 and deposited thereby in a V-shaped set edge 53. Carrier fingers (not shown and not forming a part of this invention) mounted on the end of a transfer slide snap over the blank on their stroke toward the set edge, and in their stroke away from the set edge carry the blank, hot end up, underneath the reciprocating heading die and in position directly over the orifice 75' of the stationary solid die 75. As the heading die descends, the cold end of the blank is forced into the orifice of the die and carrier fingers return for another blank. The heading tool continues down and forms the head. The headed articles are knocked out of the orifice of the stationary heading die when the movable heading die has been moved out of its

heading position and carried away by suitable means. The timing of the apparatus may be such that a blank is placed in position on the set edge after the preceding 5 blank has been carried to the heading die.

It is understood that the movements of the mechanisms of the heading machine, of the heating apparatus and of the automatic cut off of the hopper chute are interdependently 10 so adjusted and timed as to produce a smooth continuous performance of the apparatus as a whole.

The blanks are delivered from a blank cutting machine into the hopper or drum 1. 15 There the blanks are during the rotation of the drum freed of the dirt and scale, as described, and the blanks which happen to enter a radial slot at the time it is in alignment with the hopper chute are carried down into 20 the hopper to await their turn to pass through the automatic cut off 8 on to the blank carrier chain.

The blank carrier chain 10 is intermittently moved so that a pocket 11 thereof is 25 directly below the chute 7 when the chain is at rest and the cut off 8 is operated to release a blank at that very moment. The chain advances gradually through the combustion chamber 13 and the ends of the 30 blanks exposed to the furnace flame are gradually heated to the desired forging temperature. The heated blanks are delivered by the chain, hot end up, to the V-shaped set edge 53 and then carried to the 35 heading die.

By this method of heating the ends only 40 of the blanks, the objects of the invention as set forth at the beginning of the specification are fully attained. The heating is conducted under such conditions that the wasteful formation of scale is largely done away with. The operation is continuous 45 since a steady stream of blanks is fed to the

heading machine. All danger of sticking 45 in the die is eliminated since the shank portion of the blank is cold and is able to withstand, without distortion, the strain due to the formation of the head, while these strains are relatively small since the head portion of the blank is at such a temperature 50 that it will readily flow.

In this manner the articles produced possess the redeeming features of all methods in vogue without the detrimental features of any of them; moreover, the rivets or 55 bolts can, according to my method, be made at smaller cost, since many steps heretofore used are obviated and the speed of production is increased in that a single blow solid die riveting machine may be used, with the 60 attendant advantages of economy in operating cost of this type of machine.

The apparatus disclosed for carrying out the objects of the invention is largely a dia- 65 grammatic representation of the idea on 65 which the invention is based to explain the theory and principles of operation. It is understood that the objects and the desired result can be accomplished by apparatus of radically different nature. 70

I claim:

1. In apparatus for making headed articles the combination with a solid die heading machine, of a heating furnace, a conveyor, constructed to carry a number of 75 blanks, located at one side of the combustion chamber of the furnace, means for cooling the conveyor and the portions of the blanks which do not extend into the combustion chamber, and means for successively delivering the blanks to the heading machine. 80

2. In an apparatus as claimed in claim 1, means for gauging the blanks and delivering them to the conveyor.

In testimony whereof, I affix my signature.

OTTO H. DE LAPOTTERIE.
